UNITED STATES PATENT OFFICE.

JOHN WILKINSON, OF SYRACUSE, NEW YORK, ASSIGNOR TO H. H. FRANKLIN MANUFACTURING COMPANY, OF SYRACUSE, NEW YORK, A CORPORATION OF NEW YORK.

INTERNAL-COMBUSTION ENGINE.

1,119,914.

Specification of Letters Patent.

Patented Dec. 8, 1914.

Application filed February 20, 1908. Serial No. 416,874.

To all whom it may concern:

Be it known that I, JOHN WILKINSON, of Syracuse, in the county of Onondaga and State of New York, have invented a new and useful Internal-Combustion Engine, of which the following is a specification.

My invention has for its object the production of an internal combustion engine structure which is especially simple, compact and durable, and is highly efficient in use, and it consists of the parts and combinations to be hereinafter described and particularly pointed out in the claims.

One exemplification of the invention is illustrated in the accompanying drawings wherein:

Figure 1 is a vertical sectional view through the engine cylinder and associated parts. Fig. 2 is a detail sectional view on an enlarged scale of the valve mechanism, with the parts thereof in the positions occupied thereby when the inlet valve is unseated. Fig. 3 is a perspective view of the casing of the valve mechanism and associated parts; and Fig. 4 is a detail plan view.

In the embodiment of my invention illustrated, *a*, designates an engine cylinder, *b*, the crank case associated therewith, and *c*, the crank shaft. The cylinder is preferably provided with a plurality of peripheral radiating projections, as flanges *a'*, and with an axial opening *a²* in its outer end, of less diameter than the internal diameter of the cylinder, for the reception of a part of a self-contained valve mechanism, to be hereinafter described in detail, which may be said to constitute the head of the cylinder. The wall of the opening *a²* flares outwardly, and the wall of the combustion chamber adjacent thereto is of substantially truncated conoidal shape and terminates at the inner edge of said opening.

d designates a supply pipe for the explosive mixture having a discharge opening *d'* at the end thereof adjacent the outer end of the cylinder. An exhaust conduit *e* is located at the side of the cylinder opposite to the opening *d'*, and is provided with an opening *e'* arranged substantially opposite to the former opening.

The self-contained valve mechanism comprises a hollow body *f*, surmounting the end of the cylinder, and detachably secured thereto. This hollow body is preferably in

the form of a single casting having the main portion thereof above the cylinder and it carries the inlet and exhaust valves and the means for holding the same in closed position, and thus all of the parts may be removed as a unit from the cylinder, or attached as a unit thereto. The main portion of the hollow body *f* is provided with opposite lateral extensions and with openings or ports *f'* *f²* leading through said extensions and the outer ends thereof above the cylinder and designed to register, respectively, with the openings *d'* and *e'*, and said body is further provided with a reduced lower end or depending hollow nipple or tubular part *f³* of inverted truncated, conical shape, adapted to fit within the opening *a²*, and with opposite lateral extensions or lugs *f⁴* through which suitable bolts *f⁵* pass into the wall of the cylinder for securing the body *f* to the end of the cylinder. The inner edge of the tubular part *f³* is suitably beveled to provide a valve seat *g*, and the interior of the body *f* is provided with a substantially centrally-disposed diaphragm *h* which divides the same into upper and lower passageways or compartments *i*, *j*. This diaphragm is provided with an opening, disposed with its axis substantially in alignment with that of the tubular part *f³*, and surrounded by a flange or collar *m* which depends within the tubular part *f³*, is spaced apart from the inner wall thereof, and terminates in close proximity to the mouth of said part *f³*.

The inlet and exhaust valves are, respectively, designated *n*, *r* and constitute the entire closure for the opening at the end of the part *f³*, and when the valve mechanism is assembled in the cylinder, as this opening is substantially coincident with the inner edge of the opening *a²*, the two valves *n*, *r* may be said to constitute the end wall of the combustion chamber in the cylinder. The inlet valve *n* seats upon the surface *g* and is provided with a tubular stem portion *n'* which snugly fits the bore of the part *m* and is guided therein. The bore of the part *n'* opens through the valve *n* into the combustion chamber of the cylinder, and opens into the passageway or compartment *i* of the hollow body *f* through orifices or ports *n²* provided in a conical continuation *n³* of the part *n'*. The conical part *n³* ter-

minates in a cylindrical portion n^4 of relatively small diameter which passes through an opening in the top of the body f , and the bore of a boss or flange surrounding such opening, and is surmounted by a suitable cap-piece forming a shoulder between which and the top of the body f a suitable spring n^5 is interposed which tends to hold the valve n upon its seat. The exhaust valve r 5 controls the passageway through the inlet valve n and has a stem r' guided in the restricted part n^4 of the stem of the inlet valve, and in a depending sleeve n^6 which is provided within the stem of said inlet valve 10 and terminates in close proximity to the inlet valve. Said stem r' is provided at its outer end with a cap-piece forming a bearing shoulder for a spring r^2 , which tends to hold the valve r seated. This spring finds a 15 bearing at its opposite end against a laterally projecting arm of a bracket t' , said arm being disposed above the cap piece engaged by the spring n^5 and having an opening through which the stem r' is guided, this 20 bracket being secured in the body f and forming in effect an integral part thereof.

The valves n , r are positively unseated against the action of the springs n^5 , r^2 at the proper periods by levers w , and x 25 mounted in brackets bolted to the upper wall of the conduit e , such levers being actuated from a cam-shaft 1 through the intermediary of push rods 2 connected at their upper end to the outer ends of 30 said levers, and having suitable bearing surfaces at their lower ends for coaction with the cams on the cam-shaft. As will be understood, the valve r alone is depressed at the time the exhaust is 35 to occur, but at the time the inlet port is to be uncovered both of the valves n and r are depressed by reason of the fact that the valve n in its opening movement carries the valve r with it, and thus the latter remains seated during the period the valve n 40 is removed from its seat.

The cylinder a is preferably provided with a supplemental exhaust port 3 opening from its inner end, and leading into a valve 45 casing 4 in open communication with a suitable exhaust conduit. The casing 4 is provided with a passageway having a beveled seat 6 upon which a suitable valve 7 is normally held seated by a spring 8. The valve 50 7 is unseated at the proper periods by a cam 9 on the shaft 1 acting through a suitable push rod 10. It will be understood that the valve 7 is unseated as the piston passes beyond the port 3 on the working 55 stroke, and remains unseated until after the piston passes such port on its return stroke. During this period exhaust takes place unobstructedly through the supplemental port 3. Directly after the completion of the 60 power stroke of the piston, the valve r is

unseated and remains unseated during the period required for the piston to complete its return or exhaust stroke. Upon the intake stroke of the piston the valve n is unseated, the valve r remains seated, and a 70 fresh charge is drawn into the cylinder, and, directly contacts with the valve n , stem n' , and seat g . During the compression and working strokes of the piston both valves n , r are held upon their seats by the springs 75 before described, and by the pressure within the piston-chamber.

To those skilled in the art the following will be apparent, viz: The supplemental exhaust port 3, at the inner end of the cylinder 80 effects the escape at such end of a material part of the heated exhaust gases, causes a rapid and great reduction of the pressure within the cylinder before the exhaust valve r is opened, and avoids the necessity of forcing all of the heated gases at great pressure through a single port of small area in the outer end of the cylinder, and of subjecting an exhaust valve, as r , exposed at the inner surface of said outer end, to the intense heat 90 to which it would otherwise be subjected, this heat being frequently sufficient in an air-cooled engine to distort and destroy such exhaust valve in a few hours. Said port 3 thus materially reduces the liability of 95 undue or ununiform heating of the air-cooled walls of the cylinder and of the comparatively light exhaust valve r , and greatly adds to the durability of the valve r and the efficiency of the engine. The exhaust valve 100 r arranged at the outer end of the cylinder in alignment with the axis thereof, permits of a maximum scavenger action when the piston operates to discharge the exhaust gases. The hollow inlet valve encircling 105 such exhaust valve affords a maximum area for the admission of the gases, and the concentrically arranged passage-ways for the gases are so disposed that the incoming gases pass over and cool the surfaces heated 110 by the exhaust through the outer end of the cylinder. An air-cooled engine equipped with a supplemental exhaust port and concentrically-arranged inlet and exhaust valves 115 and passageways disposed and constructed as described, is capable of developing maximum power, as required in propelling the modern commercial automobile, and such engine operates with a minimum liability of undue or ununiform heating of the air-cooled walls of the cylinder, or undue heating, distortion and destruction of the concentrically-arranged valves, or reduction in the efficiency of the engine, especially when 120 developing maximum power.

The construction and operation of an engine equipped with my invention will be understood from the foregoing description taken in connection with the accompanying drawings, and it will be appreciated that cer-

tain of the parts may be varied, changed or omitted without departing from the spirit and scope of the invention.

What I claim is:—

5. 1. In an engine, a cylinder having its end wall integral with the side walls thereof and provided with an axial opening, a hollow body detachably mounted upon said end wall and including a portion extending into the axial opening, and a major portion spaced apart from the cylinder and said end wall of the same, and provided in its opposite sides with inlet and exhaust ports, said body having passage-ways therein leading from the ports to the interior of the cylinder through said portion extending into the axial opening, inlet and exhaust conduits detachably engaging the body and communicating respectively with said ports therein.
- 10 20 25 30 35 40 45 50 55 60 65 70 75 80 85 90 95 100 105 110 115 120 125 130
15. 2. In an internal combustion engine, the combination with a cylinder having an outwardly flaring opening in the head thereof; of a self-contained valve mechanism comprising a hollow body having the main portion thereof above the cylinder and having a reduced lower end complementary to and fitting within said opening, the hollow body having inlet and exhaust ports opening through opposite portions of the side wall thereof located exteriorly of the cylinder and the head thereof, and also having internal passages communicating with the inlet and exhaust ports respectively and adapted to communicate with the cylinder, an inlet valve in the body coaxial with the cylinder for controlling the passage communicating with the inlet port, an exhaust valve mounted concentrically in the inlet valve for controlling the passage communicating with the exhaust port, and inlet and exhaust conduits connected to the inlet and exhaust ports, and detachably connected to said exteriorly located portions of the cylinder, substantially as and for the purpose set forth.
- 30 35 40 45 50 55 60 65 70 75 80 85 90 95 100 105 110 115 120 125 130
35. 3. In an internal combustion engine, the combination with a cylinder having an outwardly flaring opening in the head thereof; of a self-contained valve mechanism comprising a hollow body having the main portion thereof above the cylinder and having a reduced lower end complementary to and fitting within said opening, the main portion of the body being provided with opposite lateral extensions above the outer end of the cylinder and with additional lateral extensions, and said hollow body having inlet and exhaust ports opening through said additional lateral extensions and also having internal passages communicating with the inlet and exhaust ports respectively and adapted to communicate with the cylinder, an inlet valve in the body coaxial with the cylinder for controlling the passage communicating with the inlet port, an exhaust valve mounted concentrically in the inlet valve and controlling the passage communicating with the exhaust port, screws passing through the first-mentioned lateral extensions of the body into the opposing surface of the cylinder, and inlet and exhaust conduits connected to the inlet and exhaust ports, substantially as and for the purpose described.
- 40 45 50 55 60 65 70 75 80 85 90 95 100 105 110 115 120 125 130
40. 4. The combination in an internal-combustion engine, with a cylinder having an opening in the end thereof, said opening being of less diameter than the internal diameter of the cylinder and being provided with an outwardly flaring wall, and an inlet pipe and an exhaust conduit provided with openings; of a valve mechanism comprising a body having inlet and exhaust ports adapted to register, respectively, with the openings of said inlet pipe and exhaust conduit, said body carrying contiguous portions of the inlet pipe and the exhaust conduit and being provided with a depending tubular part decreasing in diameter toward its end and fitting the outwardly flaring wall of the opening in the cylinder, and with a diaphragm provided with an opening and a depending flange arranged substantially concentric with the inner wall of said tubular part, a hollow valve and valve stem, said stem being guided in the flange, a second valve seating within the first-named valve, and means for operating the valves, substantially as and for the purpose described.
- 45 50 55 60 65 70 75 80 85 90 95 100 105 110 115 120 125 130
45. 5. In an internal-combustion engine, the combination with an engine cylinder having an opening through one end thereof, said opening being of less diameter than the internal diameter of the cylinder and being provided with an outwardly flaring wall, an inlet pipe having its discharge opening arranged adjacent to one side of said end of the cylinder, and an exhaust conduit having an opening arranged adjacent to the opposite side of said end of the cylinder; of a self-contained valve mechanism including a hollow body surmounting the end of the cylinder and having inlet and exhaust ports adapted to register respectively with the openings of said inlet pipe and exhaust conduit, said body carrying contiguous portions of the inlet pipe and the exhaust conduit, and said body being provided with a depending tubular part decreasing in diameter toward its end and fitting the outwardly flaring wall of the opening in the cylinder and being also provided with a diaphragm.

dividing the inner chamber thereof into two passageways or compartments with which the openings of the inlet pipe and the exhaust conduit, respectively, communicate, 5 said diaphragm having an opening therethrough, a valve controlling the discharge from the inlet passageway in the body and having a passageway therethrough for communicating with the exhaust passageway in 10 the body, means tending to hold the valve seated, means for unseating the same at proper periods, a second valve controlling the passageway through the first-named valve, a stem carrying the second valve, 15 means tending to hold the second valve seated, and means for positively unseating the same at the proper periods, substantially as and for the purpose set forth.

6. In an internal combustion engine, the 20 combination with a cylinder having an opening in the head thereof; of a self-contained valve mechanism comprising a hollow body supported by the head of the cylinder and having inlet and exhaust ports and internal 25 passages communicating with the inlet and exhaust ports respectively and adapted to communicate with the cylinder, valves supported by the body within the same and controlling the flow through the passages re- 30 spectively, the valves being arranged in concentric relation, and one having a tubular stem projecting outside of the body and the other having a stem slideable axially in the tubular stem and projecting beyond the 35 outer end of the tubular stem, means coacting with the stems for actuating the valves in one direction, and springs for returning the valves in the opposite direction, the springs coacting with the stems respectively 40 and being located one above the other outside of the body, substantially as and for the purpose specified.

7. In an internal combustion engine, the combination with a cylinder having an opening in the head thereof; of a self-contained 45 valve mechanism comprising a hollow body supported by the head of the cylinder and having inlet and exhaust ports and internal passages communicating with the inlet and exhaust ports respectively and adapted to 50 communicate with the cylinder, valves supported by the body within the same and controlling the flow through the passages respectively, the valves being arranged in concentric relation, and one having a tubular 55 stem projecting outside of the body and a shoulder mounted on the stem and spaced apart from the body, and the other valve having a stem slideable axially in the first-mentioned stem and projecting beyond the 60 outer end of the same and a shoulder on the outer end of the last-mentioned stem, a bracket carried by the body and having a spring seat opposed to the last-mentioned shoulder and located above the shoulder on 65 the tubular stem, means coacting with the stems respectively for actuating the valves in one direction, a spring interposed between the shoulder at the outer end of the tubular 70 stem and the opposing surface of the body, and a spring interposed between the spring seat on the bracket and the shoulder at the outer end of the inner stem, substantially as and for the purpose set forth.

In testimony whereof, I have hereunto 75 signed my name in the presence of two attesting witnesses, at Syracuse, in the county of Onondaga, in the State of New York, this 7th day of February, 1908.

JOHN WILKINSON.
